Specification for Design.

Patented Oct. 24, 1911.

Application filed August 24, 1911. Serial No. 645,845. Term of patent 7 years.

To all whom it may concern:

Be it known that I, GEORGE EDWIN GAYLORD, a citizen of the United States, residing at Elmira Heights, in the county of Chemung and State of New York, have invented a new, original, and ornamental Design for Glass Vessels or Similar Articles, of which the following is a specification, reference being had to the accompanying drawing, forming part hereof.

Figure 1 is a plan view of an article embodying the design; and Fig. 2 is a side view of the same.

The design as illustrated in the drawing is a rambler rose with the petals of the flower having a dull finish and the center a polished finish.

I claim:

The ornamental design for a glass vessel or similar article, as shown and described.

GEORGE EDWIN GAYLORD.
